UNITED STATES PATENT OFFICE.

CHARLES A. DEARBORN, OF NEW YORK, N. Y., ASSIGNOR, BY MESNE ASSIGNMENTS, TO EMPIRE MACHINE COMPANY, OF PROVIDENCE, RHODE ISLAND, A CORPORATION OF RHODE ISLAND.

FEEDING MECHANISM FOR HAT-SWEAT-SEWING MACHINES.

No. 910,463.

Specification of Letters Patent.

Patented Jan. 19, 1909.

Original application filed July 9, 1902, Serial No. 114,875. Renewed December 12, 1907, Serial No. 406,201.

Divided and this application filed June 27, 1908. Serial No. 440,739.

To all whom it may concern:

Be it known that I, CHARLES A. DEARBORN, a citizen of the United States, and a resident of New York city, in the county of New York and State of New York, have invented certain new and useful Improvements in Feeding Mechanism for Hat-Sweat-Sewing Machines, of which the following is a specification.

10 The present application constitutes a division of the application, Serial No. 406,201, filed by Charles A. Dearborn on December 12, 1907, for Letters Patent No. 894,819, dated August 4, 1908 for improvements in

15 sewing machines.

The invention relates to improvements in feeding mechanism for hat sweat sewing machines, and consists in the novel features, arrangement and combinations of parts 20 hereinafter described and particularly pointed out in the claims.

I present my invention in this application as embodied in a hat sweat sewing machine comprising the needle mechanism, looper 25 actuating mechanism, a looper, and novel means for feeding the hat along the point of sewing, said feeding means constituting my present invention and comprising as an essential feature, a positively driving circular 30 ring or frame supporting the hat and effecting its intermittent feed motion along the point of sewing. The circular feed ring or frame for feeding the hat will be driven from the driving shaft of the machine, as by a 35 pawl and ratchet mechanism, and preferably the said feed ring or frame will be supported within the upper edges of a tilttable but otherwise stationary circular frame equipped with a suitable handle by which it may be 40 tilted, and a spring for pressing the edge of the feed ring or frame in a direction against the presser foot.

The invention will be fully understood from the detailed description hereinafter 45 presented, reference being had to the accompanying drawings, in which:—

Figure 1 is a side elevation of a hat sweat sewing machine constructed in accordance with and embodying the invention; Fig. 2 50 is a top view of same; Fig. 3 is a side elevation of same, this figure showing the opposite side of the machine to that illustrated in Fig. 1; and Fig. 4 is a detached sectional

view through a portion of same on the dotted line 4—4 of Fig. 3.

In the drawings 15 denotes the general frame of the machine, this frame comprising the base 16 having at its rear end the integral member consisting of the vertical standard 17 and forwardly extending horizontal 60 arm 18, and said base 16 having at its front end the forwardly projecting segmental arms 19, 20, at whose forward ends are the vertical standards 21, 22, which at their upper ends receive the screw trunnions 23 65 supporting upon their inner ends the circular frame 24, which is capable of having a tilting or rocking motion upon the said trunnions 23 but is otherwise stationary.

The frame 24 supports and guides the 70 circular feed ring 25, which has a toothed upper edge to engage the hat, and an annular projecting shoulder 26 which rests upon the upper edge of the frame 24 and is formed with ratchet teeth throughout its entire extent. The lower edge of the feed ring 25 sets within the upper edges of the frame 24, while the said shoulder 26 rests upon the upper edge of said frame, and the feed ring 25 which is adapted to rotate upon the upper 75 edge of the frame 24, is held in position upon the latter by means of the lips 27 (Figs. 1 and 3), which are fastened at their lower ends by screws to the frame 24 and at their upper ends pass around the annular shoulder 80 26 and enter an annular groove 28 formed in said ring 25 above said shoulder. The lips 27 by passing over the annular shoulder 26 prevent the ring 25 from escaping upward 85 from the frame 24 but do not interfere with 90 the intermittent rotation of said ring upon the upper edge of said frame.

The feed ring 25 receives its intermittent motion from the driving shaft 29 through the eccentric 30 thereon, the eccentric rod 31 95 (Fig. 3) connected at its upper end with said eccentric and at its lower end pivotally secured to the rod 32, the said rod 32 and the pawl 33, the latter being carried by the extension 34 at the front end of said rod 32 100 and being in engagement with the ratchet teeth on the annular shoulder 26 of said feed ring 25. The rod 32 extends frontwardly from the eccentric rod 31 and at the lower portion of its front end is formed with the 105 extension 35 which is equipped with a bear-

ing hub 36 mounted upon the horizontal stud 37. The eccentric rod 31 is given a substantially vertical movement from the eccentric 30, and the rod 32, is, by means of 5 the rod 31, given an oscillatory or rocking motion on the stud 37, thereby causing the pawl 33 to have a forward and backward movement and enabling said pawl on its forward thrust to impart a limited rotary 10 motion to the feed ring 25. While moving rearwardly the pawl 33 will slip over the ratchet teeth on the ring 25, and at such time the said ring will be prevented from having any reverse movement by means of 15 a locking dog or pawl 38 pivotally secured upon the upper end of the vertical standard 22. The pawl 33 is secured upon the upper end of a pin 39 carried by the extension 34 of the rod 32, and upon this pin 39, 20 as shown in Fig. 3, is provided a spring which acts to yieldingly press the engaging edge of the pawl 33 against the ratchet teeth of the shoulder 26. During the rotation 25 of the driving shaft 29 the feed ring 25 is, by the means just described, given an intermittent rotary motion upon the upper edge of the circular frame 24 for the purpose 30 of feeding the edges of the hat and hat sweat to the sewing mechanism.

Upon the front end of the horizontal arm 18 of the machine frame is secured a stationary presser-foot 40 having a concave lower end or lip 41 upward against which the inner or rear edge of the feed ring 25 35 presses, said feed ring 25 having a yielding or spring tension upward at its inner or rear edge against the said presser-foot owing to the interposition of the coiled spring 42 between the base of the general frame of the machine and the handle 43 (Fig. 1) fastened to the circular frame 24. The coiled spring 42 is held upon a pin 44 which extends freely through the handle 43, and the said 40 spring is permitted to yieldingly press the inner or rear edge of the feed ring 25 upward against the presser-foot because of the fact that the circular frame 24 supporting said feed ring is pivotally mounted between the upper end of the standards 21, 22. In the 45 employment of the feed ring 25 the crown of the hat is pressed downward within said ring and the circular frame 24, and the brim of the hat is folded down upon the exterior sides of the said feed ring and frame, the 50 then upper edges of the hat along the line of the inner edge of the brim and the outer edge of the hat sweat at the rear edge of the feed ring 25, being by means of the spring 42, held up against the concave lower 55 edge of the lip 41 of the presser-foot 40. In order to enable the convenient application of the hat to the feed ring 25, below the presser-foot 40, I mount the circular frame 24 in a pivotal manner and provide said 60 frame with the handle 43, the latter enabling

the operator to press downward the inner or rear side of the frame 24 and ring 23, whereby a substantial clearance is secured between the upper edge of the ring 25 and the lower end of the presser-foot 40 for the 70 introduction of the hat below said foot. The spring 42 exerts firm upward pressure against the frame 24, but the force of this spring may be readily overcome by the operator owing to the fact that the handle 43 75 is of substantial character and extends rearwardly to a sufficient extent to enable, when pressure is applied thereupon, the convenient lowering of the inner or rear end of the frame 24 against the stress of the spring 42. 80

The driving shaft 29 will be equipped with a usual belt and hand wheel 45, the aforesaid eccentric 30, the eccentric 46 from which the rock shaft 47 will be actuated, a balance weight 48 in the form of a half disk, and an 85 oblique eccentric 49 receiving the eccentric strap 50 and coöperating therewith to impart the proper movement, as hereinafter explained, to the looper 51. The belt and hand wheel 45 and balance weight 48 are usual in 90 this art and require no special description. The eccentric 46 is rigid on the end of the driving shaft 29 and is connected by a strap 52 with the longitudinally reciprocatory rod 53 whose front end is pivotally connected by 95 a pin 54 with the lower end of a crank arm 55, whose upper end is rigidly secured upon the end of the rock shaft 47, the purpose of the eccentric 46, rod 53 and crank arm 55 being to impart the proper rocking motion to the 100 shaft 47 and the parts connected therewith. The shaft 47 is mounted in bearings at the front end of the arm 18 of the general frame of the machine, and upon its left hand end the said shaft 47 carries the said crank arm 105 55, while upon the right hand end of the said shaft 47 is secured the crank arm 56 carrying the needle 57 which preferably will be curved, as in Fig. 1. The needle 57 under the rocking motion of the shaft 47 will perform its 110 known motion, carrying the thread back and forth through the fabric.

The looper 51 is carried in the forward end of the looper rod 68, whose other end is pivotally connected with the eccentric strap 50 on 115 the oblique eccentric 49, and the forward portion of the looper rod 68 is supported on the outer end of a crank pin 74 carried by the crank arm 75 (Fig. 2) which is adapted to have a swinging or oscillatory motion so that 120 the looper rod may perform its forward and backward motions under the influence of the eccentric 49. The connection of the looper rod 68 with the crank pin 74 is by means of a ball and socket joint, whereby said rod is permitted to have the proper angular movement 125 under the influence of the oblique eccentric 49. The present invention is not limited to any special needle and looper mechanisms, and hence a more detailed explanation of 130

these parts of the sewing machine illustrated is not necessary herein.

The special sewing mechanism illustrated in the drawings is shown and described in the 5 aforesaid Letters Patent No. 894,819 granted August 4, 1908 to Charles A. Dearborn.

The present invention, as will be understood from the foregoing description, pertains more essentially to the feeding mechanism 10 of the machine, and this feeding mechanism is not limited to the employment therewith of any special sewing mechanism.

The operation of the machine hereinbefore described will be largely understood from the 15 foregoing explanations, and hence but a brief further reference to the operation of the machine will be necessary. When the machine is employed for sewing linings or sweat bands into hats, the crown of the hat will be 20 pressed downward through the feed ring 25 and supporting frame 24 and the brim of the hat will be turned downward over the outer edges of the said ring 25. In order to facilitate the introduction of the hat to the feed 25 ring 25 and below the lip 41 of the presser foot, the operator will tilt the said ring and the frame 24 downwardly and rearwardly by pressing upon the handle 43 and compressing the spring 42, and after the hat has been introduced to position the spring 42 will maintain in a suitable manner the firm relation of the hat to the feed ring and presser-foot. The hat being in position and the machine being set in motion, the needle 57 will be 30 caused to perform its motion from the driving shaft 29, rock shaft 47 and needle carrying arm 56, while at the same time the oblique eccentric 49 will drive the looper rod and the ordinary eccentric 30 will, through intermediate mechanism, impart an intermittent feed motion to the ring 25 and the hat held thereon. The feed ring 25 is driven by 35 means of a pawl 33, and this pawl is given its motion from the eccentric 30, the rod 31 and 40 rocking arm or frame 32. The movement of the sewing needle is not of unusual character.

The feed ring 25 by having a toothed or roughened edge or surface to engage the hat and being positively driven from the driving 50 shaft of the machine assures in a convenient and certain manner the correct feeding of the hat to the sewing needle, and I regard the positively driven feed ring 25 for supporting and feeding the hat as of great importance 55 and novel.

I am aware that hats have been supported within circular frames, but in accordance with my invention the ring 25 not only supports the hat but is a positively driven feed 60 element for the hat. By providing the feed ring 25 with the toothed or roughened edge or surface for engaging the hat, the latter is compelled to travel with the ring, it being the purpose of this portion of my invention 65 that the ring and hat shall travel together

and that the hat shall not travel independently of the ring or the ring independently of the hat.

What I claim as my invention and desire to secure by Letters Patent, is:—

1. In a hat sweat sewing machine, suitable sewing mechanism, combined with feeding mechanism comprising a circular feed-ring having a toothed upper edge and entirely open to receive the crown of an inverted hat 70 with the brim of the hat extended over said upper edge, ratchet teeth on the side of said ring, a presser-foot to aid in binding the hat on said upper edge, an open circular frame supporting and guiding said open ring, a pawl coöperating with said side ratchet teeth and means for operating said pawl from the main shaft of the machine for intermittently rotating said open ring; substantially as set forth. 85

2. In a hat sweat sewing machine, suitable sewing mechanism, combined with feeding mechanism comprising a circular feed-ring having a toothed upper edge and entirely open to receive the crown of an inverted hat 90 with the brim of the hat extended over said upper edge, ratchet teeth on the side of said ring, a presser-foot to aid in binding the hat on said upper edge, an open circular frame supporting and guiding said open ring, means 95 pivotally supporting said open frame so as to permit it and said ring to be tilted, a spring acting to press a portion of the upper edge of said ring against said presser foot, manually operative means for depressing 100 said edge of the ring from said presser foot, a pawl coöperating with said side ratchet teeth and means for operating said pawl from the main shaft of the machine for intermittently rotating said open ring; substantially as set forth. 105

3. In a hat sweat sewing machine, suitable sewing mechanism, combined with feeding mechanism comprising a circular feed-ring having a toothed upper edge and entirely 110 open to receive the crown of an inverted hat with the brim of the hat extended over said upper edge, a presser foot to aid in binding the hat on said upper edge, an open circular frame supporting and guiding said open ring, 115 and pawl and ratchet mechanism operable from the driving shaft for imparting to said ring an intermittent rotary motion timed with the sewing mechanism; substantially as set forth. 120

4. In a sewing machine, suitable sewing mechanism, combined with the open circular feed ring to receive, support and feed the work, a presser foot, a tiltable frame supporting and guiding said feed ring, the handle 125 connected with said frame for aiding in tilting the same, the spring pressing one portion of said feed ring and frame toward the presser foot, and means for imparting to said feed ring an intermittent rotary motion 130

timed with the action of the sewing mechanism; substantially as set forth.

5. In a hat sweat sewing machine, suitable sewing mechanism, combined with feeding mechanism comprising a circular feed-ring having a toothed upper edge and entirely open to receive the crown of an inverted hat with the brim of the hat extended over said upper edge, a presser foot to aid in binding 10 the hat on said upper edge, an open circular frame supporting and guiding said open ring, means tiltably mounting said frame, means holding said frame normally stationary with the edge of said ring pressed against said 15 presser foot, and pawl and ratchet mechanism operable from the driving shaft for imparting to said ring an intermittent rotary motion timed with the sewing mechanism; substantially as set forth.
- 20 6. In a sewing machine, suitable sewing mechanism, combined with the open circular feed ring to receive, support and feed the work and having the annular toothed shoulder 26, the open frame receiving the lower 25 edges of said ring and upon its upper edge

receiving said shoulder, the presser-foot, the pawl engaging said toothed shoulder, and means for operating said pawl from the driving shaft to compel said ring to have an intermittent rotary motion timed with the 30 action of the sewing mechanism; substantially as set forth.

7. In a sewing machine, suitable sewing mechanism, combined with the open circular tiltably mounted ring to receive and support 35 the work, a presser foot, the handle for aiding in pressing one edge of said ring downward from said presser-foot, the spring normally pressing said edge of said ring toward said presser-foot, and means for feeding the 40 work supported on said ring; substantially as set forth.

Signed at New York city, in the county of New York, and State of New York, this 24th day of June A. D. 1908.

CHARLES A. DEARBORN.
